JOHN C. MANLEY, JOHN THULIN, AND PETER J. SMITH, OF CHICAGO, ILLINOIS,
ASSIGNORS TO INVENTORS DEVELOPMENT CO., OF CHICAGO, ILLINOIS.

LAMP-LOCKING DEVICE.

1,040,367.

Specification of Letters Patent.

Patented Oct. 8, 1912.

Application filed December 14, 1911. Serial No. 695,797.

To all whom it may concern:

Be it known that we, JOHN C. MANLEY, JOHN THULIN, and PETER J. SMITH, citizens of the United States, residing at Chicago, in the county of Cook and State of Illinois, have invented a certain new and useful Improvement in Lamp-Locking Devices, of which the following is a full, clear, concise, and exact description, reference being had to the accompanying drawings, forming a part of this specification.

This invention relates to lamp locking devices and more particularly is an improvement over application #555,083, filed April 12, 1910. In said co-pending application means are provided to prevent the unauthorized withdrawal of devices such as incandescent lamps from their respective sockets by virtue of an indenting element which indents the thin lamp shell and occupies the indentation, thus to hold the lamp in place. The device is preferably key operated.

In the present application means are provided whereby these features may be applied to standard forms of porcelain sockets in such a way that the locking device is permanently associated with the socket itself.

The invention will now be described in connection with the accompanying drawing illustrating its preferred form, in which—

Figure 1 is a side view of a socket constructed and arranged in accordance with our invention; Fig. 2 is a sectional view more clearly to illustrate the features involved; Fig. 3 is an enlarged view of the locking mechanism of Fig. 2, and Fig. 4 is a sectional view of a modification.

In the illustration a plate 1 is set forth upon which sockets are to be mounted, which sockets are of the porcelain variety and are made preferably in two pieces. A socket 2 is illustrated in the figures and this socket has an upper member 3 provided with a metallic screw threaded member 4 and an outer porcelain collar 5 having a screw threaded interior to engage the member 4, thereby to hold the socket in place upon the plate 1. The metallic shell 4 has holes 6, 6 whose purpose will be more clearly understood hereafter. The lamp 7 is adapted for association with the socket and engages the screw-threaded element 4 when in place. The invention is designed to prevent the unauthorized withdrawal of these lamps and to

this end an indenting member 8 is provided having key controlled means 9 operable by means of a key 10. The indenting member 8 is screw threadedly associated with a washer 11, which washer is inserted from 60 within the element 5 into a recess 12, which recess is narrowed to provide the shoulders 13 and then continues as a recess of less cross section 14 into which the key 10 may be inserted. The washer 11 thus holds the indenting member 8 in place. The indenting member 8 is preferably provided with a sharp projection 15 which when actuated is adapted to indent the thin metal shell 16 of the lamp 7. This is more clearly shown in 65 Fig. 3. The member 8 then occupies the indentation and prevents withdrawal of the lamp 7. The key 10 and its co-operating portion 9 may be of any suitable construction to guard against misuse. When the 70 socket portion 5 is screwed into place, it must be stopped at such a point that the indenting member 8 registers with one of the holes 6 so that the indenting member may pass through this shell 4 to engage the lamp 70 shell 16. A spring washer 17 is included between the elements 3 and 5 in order that the elements may be held tightly in place even though these elements themselves do not both engage the plate 1, as it may be 85 necessary to have one element slightly removed as one of the holes 6 must register with the member 8.

In Fig. 4 we show a modification in which a socket member 18 is mounted on one side 90 of the plate 1 and a metallic shell 19 holds this socket member in place. This socket member then has the indenting member and allied parts the same as illustrated for the construction of Figs. 1 and 2. In this latter structure of course there need not be a plurality of registering apertures 6 as in the case of the structures of Figs. 1 and 2.

The importance of the device will be more apparent when it is taken into account that 100 the present day lamps of the tungsten variety are very expensive and are the source of much unauthorized removal.

It will of course be apparent that changes may be made in the device herein disclosed 105 without departing from the broad features of the invention herein, and the specific description given above of the particular form set forth herein is not intended to limit the invention to this particular form.

Having, however, thus described one embodiment of our invention, we claim as new and desire to secure by Letters Patent the following:

- 5 The combination with a socket having a body portion constructed of insulating material of a lamp adapted for association with said socket, and locking means to prevent the unauthorized withdrawal of the lamp
10 from said socket mounted within said insulating body portion, said locking means including a key controlled inclined indenting member adapted to indent the lamp shell when actuated and to occupy the indentation, a metallic element with which said in-

denting member has screw threaded engagement mounted within said body portion, and offsets provided in said insulating body portion to prevent withdrawal of said metallic element from without.

In witness whereof, we hereunto subscribe our names this 8th day of December A. D., 1911.

JOHN C. MANLEY.
JOHN THULIN.
PETER J. SMITH.
